UNITED STATES PATENT OFFICE

162,356

RAZOR BLADE SHARPENER

Richard Smith, Tucson, Ariz.

Application July 28, 1950, Serial No. 11,459

Term of patent 14 years

(Cl. D37—1)

To all whom it may concern:

Be it known that I, Richard Smith, a citizen of the United States of America, residing at Tucson, in the county of Pima and State of Arizona, have invented a new, original, and ornamental Design for a Razor Blade Sharpener, of which the following is a specification, reference being had to the accompanying drawing, forming part thereof.

Figure 1 is a perspective view of a razor blade sharpener embodying my design.

Fig. 2 is a rear elevational view thereof.

I claim:

The ornamental design for a razor blade sharpener, as shown.

RICHARD SMITH.
